(57) **CLAIM**

The ornamental design for a pizza oven, as shown and described.

DESCRIPTION

FIG. 1 is a front, right and top perspective view of a pizza oven, showing our new design;

FIG. 2 is a rear, left and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a front, right and top perspective view of the pizza oven, showing our new design in an exploded configuration with environment of a lid.

The broken lines in the drawings depict portions of the pizza oven that form no part of the claimed design. The additional broken lines showing of a lid in FIG. 9 depict environmental structure that form no part of the claimed design.

1 Claim, 9 Drawing Sheets
